STOKER

William O. Martin, Fort Smith, Ark., assignor to
 William O. Martin, Incorporated, Fort Smith,
 Ark., a corporation of Arkansas

Application September 12, 1940; Serial No. 356,492

6 Claims. (Cl. 110—105.5)

My invention pertains to mechanical stokers for the fire-boxes of boilers and more particularly stokers for locomotives and relates to the distributor structure or distributing plate whereby the fuel or coal is introduced into the fire-box through the usual fire-door opening in the back wall of the fire-box; the application being a continuation-in-part of my pending application Serial Number 268,949, now Patent No. 2,242,587, May 20, 1941.

My invention has for its object the provision of a distributing structure or plate adapted to receive the fuel or coal and having means associated therewith whereby controllable jets of steam, or other suitable medium under pressure, will be discharged across the plate and proper distribution of the coal or fuel inside the fire-box induced; the distributing plate also involving adjustable and removable means whereby a deflection of portions of the coal or fuel toward opposite sides of the fire-box will be induced.

Another object of my invention is the provision of a distributing structure which is adapted to the varying dimensions of locomotive fire-boxes and wherein that portion of the distributor structure subjected to the greatest heat may be renewed when necessary without need for replacing the entire structure which also involves pressure medium or steam jet providing elements which also function as fastening elements or anchor bolts for securing the distributor structure, as well as a coal delivering hood disposed about the firing opening, in place; the anchor bolts eliminating the necessity of using steam headers and gaskets and also enables a standardized distributing plate to be used with any dimension fire-box, due to the fact that a slight turn of any anchor bolt will provide fuel distribution in any desired manner.

The foregoing enumerated objects and the advantages inherent in the invention will all be readily comprehended from the following detailed description of the accompanying drawing wherein:

Figure 1 is a vertical sectional view of a portion of the rear wall of a locomotive fire-box with my invention, also in section, applied.

Figure 2 is a sectional elevation taken on the line 2—2 of Figure 1.

Figure 3 is a detail perspective view of a portion of the back wall of a fire-box and a part of the delivery end of the stoker mechanism with my improved distributing plate (as viewed from the fire-box interior) and portions broken away to illustrate construction.

Figure 4 is a transverse sectional view of the distributing plate.

Figure 5 is a detail sectional view of one of the distributing plate fastening and pressure medium directing elements.

Figure 6 is a detail perspective view of one of the fuel deflecting elements.

Although my improved fuel distributing mechanism is applicable for use with a stationary boiler, it is more especially adapted to stokers for locomotive fire-boxes and is therefore shown applied to the rear wall of a locomotive fire-box, a portion of which is shown at 10, provided with the usual firing opening 11, about which the delivery receptacle or hood 12 is secured; the bottom of the receptacle or hood having an opening to receive the upper end of a vertical riser 13 which communicates with an opening in the top of the horizontally disposed fuel conveying conduit of which a portion is shown at 14 and which may be of the general construction disclosed in my copending application Serial Number 268,949. The fuel or coal traveling through the horizontally disposed conduit 14 is deflected upwardly through the riser 13, pyramiding in the receptacle, in a loose state, until it falls by gravity onto the distributing table secured in the bottom of the receptacle and disposed through the firing opening 11 of the fire-box.

The distributing table preferably consists of two superposed plates 15, 16, of width commensurate with the major transverse axis of the firing opening 11 and of length sufficient to extend a short distance into the fire-box; the outer ends of the plates being preferably slightly narrower, as shown in Figure 3, to enable the plates to seat in the lower part of the fire-door opening.

The lower side of the bottom plate 15, intermediate its ends as well as the lower side of the side marginal portions of the top plate 16, preferably are made arcuate transversely as shown at 17 and 18, see Figure 4, to conform to the usual curvature of the firing openings in locomotive fire-boxes, which permits application to be made without necessitating the firing opening in the boiler-head to be enlarged. The ends of the plates are shown rectangular at 19, with the outer ends resting on and secured to the bottom of the receptacle or hood 12 intermediate of the back wall of the fire-box and the upper end of the riser 13, see Figure 1.

As the end of the lower plate 15 of the distributing table which projects into the fire-box is in close proximity to the fire it is subject to burning or warping and I therefore employ a pair of su-

perposed plates as shown which permits the lower plate to be renewed or replaced without necessitating the discarding of the entire distributing table; the structure affording a material element of economy.

The lower side of the upper plate 16 is channeled from end to end as shown at 20 for the purpose of providing an air passage between the two superposed plates; the air passage extending to the outer end of the table within the receptacle or hood 12, permits air to flow through the channel or passage, induced by the draft in the fire-box, which affords a cooling action for the distributing table and provides protection for the top plate 16. The top plate 16, as shown, is provided with a smooth upper surface.

The two plates are secured together intermediate of their ends by suitable bolts, as at 21, with their heads countersunk (see Figure 4); while the outer ends of the two plates are secured together by a number of anchor bolts 22, disposed vertically through suitable holes in the rear or outer ends of the plates and through a bracket 23 attached to the bottom of the hood or receptacle and through the flange 24 of the riser 13; the anchor bolts being arranged intermediate of the riser 13 and the back wall of the fire-box, see Figure 1.

These anchor bolts 22 (of which a number are employed) are of the construction disclosed in Figure 5, with the lower threaded ends reduced in diameter and slightly tapered, as shown at 22^a, and the bolts drilled lengthwise from the lower ends upwardly into the heads as at 22^b, Figure 5, while the heads are drilled from the sides to intersect the longitudinal bores, as shown at 25, thereby providing an upward passage, through each bolt, which terminates in one of the sides of the bolt-heads. The bolts when secured in place are so arranged that the holes or passages in the bolt-heads will be disposed toward the inner end of the distributing plate. The upper threaded portions of the bolts receive nuts whereby the bolts and associated elements are firmly held in place while the lower threaded ends 22^a of the bolts have the pipes 26 connected thereto; the pipes in turn being in communication with a suitable supply of pressure medium or steam as shown in Figure 2 where the other ends of the pipes 26 are connected with a manifold 27 which is in communication with the steam space of the boiler; the pipes 26 being provided with suitable hand valves at 28 whereby the flow of steam to each anchor bolt or steam jet element 22 may be controlled. The heads of the bolts 22 extend slightly above the upper plate 16 of the distributing member with their jets or bores 25 disposed substantially parallel and in slight spaced relation with the top of the plate. These jets provide anchor bolts, thus obviating the necessity of using steam headers and gaskets and the making of suitable joints as is the case in previous constructions and enable a standardized distributing plate to be used with any dimension fire-box due to the fact that a slight turn of any bolt will provide distribution in any desired manner.

In order to deflect the fuel or coal toward opposite sides of the fire-box, the inner end of the top plate adjacent opposite sides, preferably in proximity to the inner sheet of the fire-box wall, is provided with arcuate wings 29 curving laterally. The outer ends (namely the ends disposed toward the jets) of the wings are arranged so that a portion of the coal will be intercepted

and deflected laterally. The wings 29 consist of the upper arcuate portion provided on its bottom with a pin portion 30 threaded at its lower end; the pin 30 being of length sufficient to extend through registering holes in both plates 16 and 15, and fastened in place by suitable nuts as at 31 in Figure 1. In order to maintain the wings in the desired position in keeping with the fire-box construction, I provide the bottom of each wing with a depending stud 32, while the upper plate 16 of the distributing table is provided with a number of arcuately arranged and suitably spaced sockets as at 33, see Figure 3; the sockets 33 being arranged so that the forward ends of the wings (as viewed in Figure 3) may be moved toward or away from the inner side of the rear wall of the fire-box. With this construction, the wings are not only adjustable to properly deflect a portion of the fuel or coal to the side and back corners of any dimensioned fire-box, but may be renewed when necessary without destroying the entire distributing plate.

With my improved distributing plate a comparatively small displacement or reduction, say about two inches, at the center of the firing opening is made, which is less than the displacement ordinarily made by the protecting flange on the average fire-door frame and therefore permits ingress and egress from the fire-box as conveniently after the distributing plate has been installed as before. After the anchor bolts 22 have been set for proper distribution of coal inside the fire-box, they are tightened against the hood bracket 23 with the jam nuts as shown in Figure 1. This construction permits accurate adjustment of steam jets for any dimensioned fire-box by slightly turning the bolts before tightening the nuts; at the same time a defective jet may be renewed or repaired without dismantling or destroying the entire distributing plate; while on the other hand, the distributing plate, should occasion require, may be removed and replaced from the deck of the engine.

In operation, the fuel or coal, pyramiding in the receptacle or hood 12, falls onto the smooth upper face of the distributing table and hence into the paths of the jets of steam, or other suitable medium, issuing from the bolt-heads, causing the fuel to be more or less evenly distributed in the fire-box; the flow of steam being controlled by the respective valves 28.

The exemplification shown in the drawing is believed to be the simplest embodiment of the invention, which has been described in terms employed as terms of description and not as terms of limitation, as structural modifications are possible and may be made without, however, departing from the spirit of my invention as defined in the appended claims.

What I claim is:

1. In a stoker, a distributing table adapted to be disposed through the firing opening of a fire-box and composed of a pair of superposed plates removably secured together, the lower face of the top plate being channeled from end to end to provide an air passage between the plates, while the lower face of the bottom plate, intermediate its ends, is of arcuate formation transversely to approximate the curvature of the bottom of the firing opening in the fire-box rear wall; a plurality of anchor bolts whereby the outer ends of the plates are secured in place adjacent the bottom of the firing opening, the bolts being bored longitudinally from their lower ends, with the bores terminating in one of the side faces of the

bolt-heads to provide jets disposed toward the inner ends of the plates; and controllable connections between the lower ends of the bolts and a steam supply whereby a plurality of steam jets across the top of the distributing table may be provided.

2. In a stoker, a distributing plate adapted to extend through the firing opening of a fire-box, the outer end of the plate having bolt-receiving holes while the inner end of the plate, adjacent each side, has a hole therethrough and a plurality of sockets arcuately arranged about the hole, coal deflecting arcuate wings provided with depending stems adapted to pass through said last mentioned holes and with studs adapted to fit into said sockets whereby the deflecting wings are adjustably secured to said plate; and anchor bolts disposed through the outer end of the plate with their heads disposed above the plate whereby the latter is secured in place, each bolt being longitudinally bored from the lower end with the bore terminating in one side of the bolt-head; and controllable steam connections secured to the lower end of each bolt.

3. In a stoker, a distributing table adapted to extend through the firing opening of a fire-box and composed of a pair of superposed plates removably secured together, the top plate being provided with a flat upper surface while the lower surface of the top plate at opposite sides and the lower surface of the bottom plate are transversely arcuate to conform with the curvature of the firing opening, the opposing face of at least one of the two plates being channeled from end to end to provide an air passage extending lengthwise through the table from end to end, vertically disposed anchor bolts with their heads arranged on the upper face of the table whereby the outer end of said table is secured in place, said bolts having longitudinal bores extending upwardly from their lower ends with the bores terminating in the inwardly disposed side faces of the bolt-heads adjacent the upper surface of the distributing table; and a pressure medium supplying element secured to the lower end of each bolt whereby a plurality of pressure medium streams may be discharged across the top surface of said table.

4. In a stoker, a distributing table composed of a pair of flat surfaced plates arranged in face-to-face relation and the face of one of the plates having a channel from front to rear to provide an air passage between the plates extending from

5 end to end; a plurality of externally threaded anchor bolts whose heads are arranged on top of the table whereby the outer ends of the table plates are secured in place at the bottom of the firing opening in the back wall of a fire-box, the threaded portions of the bolts being adapted to receive jam nuts for securing the bolts in place, said bolts being bored longitudinally from their lower ends with the bores terminating in the 10 inwardly disposed side faces of the bolt heads; and pressure medium conveying pipes secured to the lower ends of the bolts, said pipes having communication with a suitable source of pressure medium.

5. In a stoker, a distributing table adapted to be disposed through the firing opening of a fire-box and composed of a pair of superposed plates arranged in face-to-face relation, the adjacent face of at least one of the plates being channeled from end to end to provide an air passage from end to end of the table, while the lower face of the bottom plate is of arcuate formation transversely intermediate the ends to approximate the curvature of the bottom of the firing opening in the fire-box; and a plurality of anchor bolts whose heads are arranged on the upper face of the table whereby the outer ends of the table-plates are secured together and to the fire-box adjacent the bottom of the firing opening, the bolts being externally threaded to receive jam nuts and for attaching steam conveying pipes thereto, said bolts being longitudinally bored from their lower ends with the bores terminating in one of the inwardly disposed side faces of the bolt heads, whereby jets of steam may be discharged across the top of the table.

6. In a stoker, a distributing table adapted to extend through the firing opening of a fire-box and having a flat upper face and an air passage extending lengthwise therethrough from front to rear; vertically disposed anchor bolts whose heads are arranged on the upper surface of the table whereby the outer end of said table is secured in place, said bolts being longitudinally bored from their lower ends with the bores terminating at the inwardly presented side faces of the bolt-heads adjacent the upper surface of the distributing table; and pressure medium supplying means connected with the lower ends of the 45 bolts, whereby a plurality of pressure streams 50 may be discharged across the top surface of the distributing table.

WILLIAM O. MARTIN.
